UNITED STATES PATENT OFFICE.

WILLIAM S. WOOTTON, OF SCOTTSBURG, ASSIGNOR TO J. M. CARRINGTON,
OF SOUTH BOSTON, VIRGINIA.

DRY-HOUSE.

SPECIFICATION forming part of Letters Patent No. 375,306, dated December 20, 1887.

Application filed March 5, 1887. Serial No. 229,851. (No model.)

To all whom it may concern:

Be it known that I, WILLIAM S. WOOTTON, of Scottsburg, Halifax county, in the State of Virginia, have invented new and useful Improvements in Dry-Houses particularly adapted to the curing and ordering of tobacco, but applicable to other purposes; and I do hereby declare that the following is a full and accurate description of the same, reference 5 being had to the accompanying drawings, in which—

Figure 1 is a perspective view of my invention, partly in section. Fig. 2 is a plan of the same. Fig. 3 is a vertical longitudinal section. Fig. 4 is a vertical longitudinal section of the boiler. Fig. 5 is a vertical longitudinal section of boiler in place in the heater.

The object is, in all devices for drying by artificial heat, to heat the air which afterward 20 passes over the substance to be dried, to evaporate and take up the moisture therefrom; but some substance require treatment different from others, because they are more affected by imperfect action of the drier. For instance, 25 if the hot air is already saturated with moisture, or nearly so, it will heat and bring to the surface of the material under treatment the moisture contained therein without power to take up and carry away the same. In drying lumber this would not be any material 30 detriment, because it would eventually be dried or removed in dressing the lumber; but in drying fruit the beads of gummy moisture thus brought to the surface will cause 35 spots which blemish the appearance. In curing tobacco the occurrence of such spots seriously injures its market value. It is therefore of importance that the air shall not be heated too high, and that it shall not be damp 40 when it passes to the substance under treatment. If the temperature is too high, the moisture is brought to the surface too rapidly, and if the warm air is already saturated with moisture it cannot take up and carry away 45 that which the warmth causes to exude.

In the treatment of tobacco it is necessary to maintain in the leaves a certain degree of humidity in order to render them pliable without being brittle, and when the leaves have 50 been once cured they will become too dry and

brittle in dry weather, so that they cannot be handled. Restoring the requisite moisture is called "ordering" or putting in order, and is usually effected by means of steam discharged into the apartment where the tobacco 55 is. It is the common practice to permit the tobacco to continue hanging in the curing house or barn until the time for packing and shipment arrives, and it is common to employ a special steam-generator when it is required 60 to "order" the tobacco.

My invention is designed to meet all the requirements of this service, first, by warming a large volume of fresh air without unduly heating it and without a return circulation, 65 and, second, by providing a steam-generating attachment, whereby the heating device may also be employed as an ordering apparatus.

A is the dry-house or kiln, constructed in any suitable way and of any proper material. 70 Large dry-houses are commonly constructed of wood. For convenience and economy of space I dig a pit, B, about two feet deep and extending under the building A to the rear end of the heater C. Grate-bars d d are placed in this 75 pit, supported either upon transverse bearers or in the side walls, E, when themselves transverse to the length. The grate-bars may be sufficiently elevated to constitute an ash-pit below them, or a special pit, E², may be dug 80 for the purpose. A door, G, closes the front of this fire-chamber.

The fire-chamber above described is such as I have used for burning wood. Modifications to adapt it to the combustion of coal will occur 85 to any person skilled in stoves and furnaces.

The iron heater C consists of a sheet-iron shell resting on the fire-pit walls E, and its inner end is open for the admission of the flame and products of combustion from the fire-pit. Said flame and hot products pass forward within said heater C to its front end and thence escape into the flues F. Thus the surface of the shell C is heated. But to furnish an abundant supply of warm fresh air a conical 95 pipe, H, is placed within said shell C and extends through the same, projecting at both ends. The smaller end projects through the outer end of the shell C and extends to and through the wall of the dry-house A, so as to 100

open in the open air without. This forms an open conduit from the external atmosphere through the hot shell C to the interior of the kiln, through which fresh air may freely pass and be heated as it passes; and the pipe H, being conical, with its larger end inward, not only presents an enlarging expanse of hot surface, but it also permits the air to expand as it augments in temperature, without checking the inflow. The upward inclination of the pipe H toward the inner end also assists its free and rapid transition through the heater.

For convenience I flatten the outer end of the heater C to the form of an ellipse, whose shorter diameter is the diameter of the pipe H where it passes from the outer end of said heater; and I close this end of the heater with an elliptical plate. The flues F are connected with these laterally extended or flattened sides of the heater, which has much larger side chambers, i, in communication with said flues than would be possible if the heater preserved its cylindrical form. The external opening into the pipe H is covered and protected by a hood, j, to prevent direct access thereto and to guard against the entrance of smoke, dust, and ashes from the fire-box. The flues are extended laterally, with a slight inclination upward, and follow around the walls A at a little distance therefrom to a point opposite the heater, and they then cross to a place over the heater, where they unite and pass out through the wall or up through the roof, as desired. By this arrangement of the flues F, I save nearly all of the heat which would otherwise be discharged into the outer air with the smoke; but of course the smoke-flues may be arranged differently without materially changing the effect, through I prefer 40 the arrangement shown.

To employ my heater in ordering tobacco or other similar purposes I provide dampers, k k in the several pipes and flues, so that passage through them can be arrested or diverted at will. I also connect the chambers i i with air-pipe H by means of pipes M M, provided with dampers and also a pipe, L, which connects said pipe H with flue F near its point of discharge. The pipe L is also provided with 45 a close-fitting damper. At the inner end of the heater C, I provide a door, N, which swings outward on a horizontal pivot and communicates with the fire-chamber. A conical boiler, O, is now provided adapted to fit within 50 the pipe H, and extended from its inner end forward to the front end of the heater C. A conical flue, p, extends through said boiler, its larger end being at the inner or larger end

of the boiler and close to its lower margin, and the smaller end of said flue being at the 60 smaller end of the boiler and near its upper margin, so that the general direction of said flue is a little upward. Its smaller end communicates with the pipe H near to its junction with the pipe L. The larger end of the flue p is provided with a hood, q, extends 65 downward so as to communicate with the door N, and then flame and hot products of combustion may pass from the pit through the door N into the hood q and flue p, and thence 70 through the pipes H and L into the flue F near its point of discharge. When the generator O is being employed, it is not desired to heat the atmosphere, and therefore the dampers in flues F are closed and the dampers in 75 pipes M are opened to permit the hot products of combustion a quick passage to the open air. A steam-dome, v, attached to the boiler, and steam drawn therefrom may be conducted to any point desired through a steam-hose or in 80 some other convenient way.

Having described my invention, I claim—

1. In a dry house or kiln, a fire-pit and a heater, C, combined with a conical air-tube, H, placed longitudinally through said heater 85 and having its smaller end extended through the wall of said dry-house and into the external air, and its larger end open for free discharge into said kiln.

2. In a dry house or kiln, a fire-pit combined with a heater, C, each end forming the figure of an ellipse, but one having its major axis vertical and the other having its major axis horizontal, and an internal longitudinal air-tube, H, and flues F, whereby the chambers i i are formed, as set forth. 90

3. The combination, in a dry-house heater, of the fire-pit and the heater C, provided with the longitudinal air-pipe H, the pipes M M and L and dampers in the same, and the door N at the rear of the fire-pit, as set forth. 95

4. The fire-pit and the heater C, provided with the conical air-pipe H, the smaller end whereof extends through the wall of the dry-house, and the hood j, closed in front but open laterally to protect the same, as set forth. 100

5. The fire-pit and the heater C, provided with a door, N, and pipes M M and L, combined with the boiler O, provided with a longitudinal flue and a hood, q, whereby the products of combustion may be caused to pass through or around said boiler, as set forth. 105
